UNITED STATES PATENT OFFICE.

ALFRED H. ANDERSON, OF LA CROSSE, WISCONSIN.

COLLAR FOR FLANNEL SHIRTS.

SPECIFICATION forming part of Letters Patent No. 463,884, dated November 24, 1891.

Application filed September 11, 1888. Serial No. 285,120. (No model.)

To all whom it may concern:

Be it known that I, ALFRED H. ANDERSON, a citizen of the United States, residing at La Crosse, in the county of La Crosse and State 5 of Wisconsin, have invented certain new and useful Improvements in Shirts, of which the following is a full and clear description, reference being had to the accompanying drawings, forming part of this specification, in 10 which—

Figure 1 represents an inside view of the upper portion of a shirt, showing the collar turned up. Fig. 2 is a similar view showing the unattached flap or inner edge of the collar thrown back to expose the internal pocket and stiffening-piece. Figs. 3 and 4 are views of stiffening-pieces removed.

My invention relates to shirts, and particularly to that class known as "negligee shirts;" 15 and my invention consists of the means hereinafter described and claimed for stiffening the collar of the shirt.

The object of my invention is to so stiffen the points and other portions of the collar of 20 a woolen or other shirt that said collar will lie in its proper position, retain its shape, and be free from the wrinkles which usually appear in the collars of woolen, part woolen, and unstarched cotton shirts.

To enable others skilled in the art to make 25 and use my invention, I will now describe the same and indicate the manner in which the same is carried out.

In the drawings, A represents the upper 30 portion of the body of the shirt, and B is the collar, the two edges a b of which are sewed to the top edge of the body portion, the said edge a being sewed throughout its length to the top edge of the body, while the inner edge 35 b is sewed to said edge on the opposite side for a comparatively short distance as between the points c c' d d', as shown in Figs. 1 and 2.

That portion of the lower inner edge b between the points c' and d' is not attached to 40 the body portion, but is left free and formed with a flap e, which is provided with button-

holes or other fastenings for securing this flap to the inner top portion of the body of the shirt. By thus constructing the collar it is obvious an internal pocket is formed, access 50 to which may be had from the inside of the shirt and through the medium of the loose flap e. In the pocket thus formed I introduce a stiffening-piece or form D, of suitable material, such as celluloid or zylonite, or, if preferred, a wire frame, said piece having a size and shape adapting it to about fill the pocket and to correspond with the curvature of the collar, whereby the latter retains its shape and position. From this description it will 60 be seen the inserted stiffening-piece or form preserves the shape of the collar and prevents the unsightly wrinkles so common with woolen, part woolen, and unstarched cotton shirts, and when it is desired to wash the shirt the 65 inner stiffening-piece or form may be readily removed by unbuttoning or loosening the flap e, thus exposing the pocket in the collar and permitting the withdrawal therefrom of said piece.

While I have shown my invention as applied to the collar of a shirt, it is evident the means described may be applied with equal effect to the cuffs.

Having thus described my invention, what 75 I claim as new, and desire to secure by Letters Patent, is—

A collar for shirts, of flannel or equivalent material, comprising a body portion of two or more plies secured together at the outer edges 80 and having the inner edge of one ply secured throughout its length to the band portion, and having an opening adjacent to said band portion, whereby a pocket and opening there-to is formed between said plies, in combination with a stiffening-piece, shaped like the collar, within said pocket, and means for retaining the same therein.

ALFRED H. ANDERSON.
